UNITED STATES PATENT OFFICE.

GEORGE STRONG, OF DETROIT MICHIGAN.

HOT-WATER HEATER.

SPECIFICATION forming part of Letters Patent No. 663,244, dated December 4, 1900.

Application filed January 22, 1900. Serial No. 2,360. (No model.)

To all whom it may concern:

Be it known that I, GEORGE STRONG, a citizen of the United States, residing at Detroit, in the county of Wayne and State of Michigan, have invented certain new and useful Improvements in Hot-Water Heaters, of which the following is a specification, reference being had therein to the accompanying drawings.

10 My invention relates to tubular hot-water heaters, and has for its object the obtaining of a construction in which the various constituent tubes are effectively disposed, and one in which the parts may be easily assembled.

15 The invention consists in the peculiar construction, arrangement, and combination of parts, as hereinafter described and claimed.

In the drawings, Figure 1 is a vertical and 20 cross section through my heater. Fig. 2 is a perspective view of the two sections comprising my heater, showing the manner of assembling the same. Fig. 3 is a horizontal section illustrating the manner of connecting the 25 risers to the headers. Fig. 4 is a horizontal section on line $x-x$, Fig. 1.

My heater comprises two sections similar in construction and adapted to be independently assembled, each section being provided with 30 a series of vertical risers having laterally-extending loops or return-bends. The loops of the two sections are so arranged as to intermesh with each other and together form the top of the fuel-chamber, the sides of which are 35 formed by the vertical portions of the tube.

In detail the construction is as follows: A A' and B B' are respectively top and bottom headers extending longitudinally of the heater and parallel with each other. Each pair 40 of headers is connected by a series of risers C and C', which are of the following construction: a is a vertical tube connected to the lower header, and extending upward to substantially the top of the fuel-chamber; b, a 45 series of laterally-extending loops, the lower one being preferably connected by an elbow c to the tube a, and the others being connected in series by elbows or return-bends d. The highest loop b is connected with a vertical 50 tube e, which extends upward and into the header A. The tubes a are arranged as close as possible to each other, so as to form, in

effect, the wall of the combustion-chamber adapted to retain the fuel therein. In order to thus closely space said tubes, I preferably 55 alternately connect them into the top and side of the header B, as shown in Fig. 2. Thus the first pipe a may be connected directly into the top of the header, and the second pipe a' is connected by an elbow f with a short lateral 60 pipe or nipple g, which in turn is connected by the elbow h into the vertical pipe i, the latter being connected by the elbow j to the side of the header. The laterally-extending pipe or nipple g is preferably formed with 65 right and left threads at its opposite ends, so that the pipe a' may be readily connected in or removed from the structure without disturbing the adjacent pipes. The connection of the vertical pipes e with the upper header 70 is similar to that between pipes a and the lower header, the only difference being that the pipe e, corresponding with the pipe a, is connected into the side of the upper header, while the pipe e', corresponding to the pipe a', 75 is connected into the bottom of the header.

From the above description it will be seen that the sections forming the opposite sides of the heater are entirely independent of each other in construction. When arranged in 80 proper relation to each other, however, the loops b of one section intermesh with the loops b of the opposite section, as shown in Figs. 1 and 2. To provide for this arrangement, each loop b is separated a sufficient distance 85 from the adjacent loop to permit of a loop from the opposite section extending therebetween. When the two sections are placed together, as shown in Fig. 1, the lateral loops b are so closely arranged in relation to each 90 other as to leave only sufficient space for the flame from the fire to pass therebetween. The vertical tubes a a' are also so near to each other that the elbows and other fittings of the adjacent pipes are preferably tough. To connect 95 the two sections to each other and with the outlet and inlet pipes, I provide at each end of the heater the arched pipe D, comprising the vertical pipes p and horizontal pipes q, said arch being connected at its lower ends with the ends 100 of the headers B and B' and centrally of the arch with the vertical pipe E. The two vertical pipes E are connected at the top by a longitudinal pipe F and near the center

thereof with a vertical pipe G, forming the return connection to the heater. The upper headers A and A' are connected with the longitudinal pipes H, preferably arranged 5 thereover and entering the opposite ends of the headers, said longitudinal pipes being cross-connected by a pipe I, which is centrally connected with a vertical pipe J, forming the outlet connection from the heater. Thus the 10 two sections of the heater are firmly connected with each other and at the same time may be readily disconnected whenever necessary.

The general proportions of my heater when completed are such as to make the length and 15 height relatively great in proportion to the width, as shown in Figs. 2 and 4. This has the effect of reducing the necessary grate-surface and also influences the working of the heater, as will be hereinafter described.

20 The sections are arranged in any suitable casing, such as K, with the lower headers B and B' resting upon ledges or supports.

M is the grate, which I have shown as of a rotary form, having laterally-projecting fingers m, extending in proximity to the opposite headers B and B'. The grate is arranged below the plane of the headers B and B', so that the latter form a portion of the fire-pot, the upper portion of which is formed by the 30 vertical tubes a a'. The space between the casing K is sufficient to make the walls clear the side connections of the risers for the headers, and this will leave chambers O outside of the wall of pipes a a' and into which

35 the flame and products of combustion may pass through the narrow slits between the pipes. In order to clear these chambers O from any accumulation of ashes or soot, I preferably provide doors P on either the front

40 or rear wall of the casing, through which a suitable cleaning implement may be introduced and the dirt removed. For feeding the fuel into the heater I arrange a door Q in the front wall of the casing, and this is 45 preferably placed just below the lowest loop b. I also preferably arrange a series of laterally-extending loops R in the front and rear risers which extend in proximity to the rear and front walls of the casing and form 50 a tubular lining to the fire-pot.

The construction of the furnace being as described, in operation the fuel is fed in through the door Q and may, if desired, completely fill the chamber bounded on the sides 55 by the tubes a a' and on the top by the tubes b. In burning, the flame and products of

combustion will pass between the tubes above and to the side and will finally make their way to the smoke-stack S. I have found in practice that a furnace of the proportions described requires but very little attention and will develop a uniform heat for a much greater length of time than if the width of the fuel-chamber were greater in proportion to its length and height and to the amount of grate- 60 surface. Moreover, as the side pipes a, as well as the headers B and B', come in direct contact with the fuel the water will be thoroughly heated, even with a slow fire. Thus my heater is especially useful for use in heating private houses where only a comparatively small amount of heat is needed and where it is desirable to have a uniform heating action with only occasional attention. At the same time the heater is equally adapted for use in 65 heating larger buildings and may be easily regulated to give any desired temperature.

What I claim as my invention is—

1. A water-heater comprising two separately-assembled oppositely-arranged sections, each 80 consisting of top and bottom headers, and a series of connecting-risers the upper portions of each riser having a series of laterally-extending loops or return-bends adapted to intermesh with the loops of the corresponding 85 riser in the opposite section, and forming an arch over the fuel-chamber, and connections between said top and bottom headers respectively forming a common outlet and common inlet connection with both sections. 90

2. A water-heater comprising top and bottom headers and a series of connecting-risers, said risers being alternately connected to the top of said bottom header and side of said top header, and side of said bottom header and 95 bottom of said top header.

3. A water-heater comprising parallel sections each consisting of top and bottom headers and a series of connecting-risers having laterally-extending loops or return-bends in 100 their upper portions, said sections being arranged to form a fuel-chamber of relatively narrow width in comparison with its length and height, and a rotary grate arranged between and extending longitudinally of said 105 lower headers.

In testimony whereof I affix my signature in presence of two witnesses.

GEORGE STRONG.
